UNITED STATES PATENT OFFICE.

CLINTON M. BALL, OF TROY, NEW YORK.

ELECTRIC-ARC LAMP.

SPECIFICATION forming part of Letters Patent No. 301,550, dated July 8, 1884.

Application filed January 25, 1884. (No model.)

To all whom it may concern:

Be it known that I, CLINTON M. BALL, of Troy, in the county of Rensselaer and State of New York, have invented an Improvement in 5 Electric-Arc Lamps, of which the following is a specification.

In my improvement there is a helix in a shunt-circuit, and the carbon-holder and the gearing and frame connected with the same 10 are supported upon a spring. The armature of the electro-magnet is connected with this frame, so that the carbon-holder is moved by the action of the magnet to bring the carbons into contact. The spring then forms the arc 15 by lifting the carbon as the current passes through the carbons and the magnet weakens. The train of gearing is held by a spring-brake, and the brake is liberated to allow the carbons to feed whenever the magnet is energized be- 20 yond a certain normal condition or strength. By my improvement the carbon is under the control of one magnet and all the functions required are performed by the same. I also provide in the shunt-circuit a thermic safety- 25 switch, that short-circuits the lamp in case of the current becoming too strong in the shunt-circuit.

In the drawings, Figure 1 is an elevation of the upper part of the lamp, the case being in 30 section. Fig. 2 is a sectional plan at the line *x x*. Fig. 3 is a vertical section at the line *y y*. Fig. 4 is a section of the ceiling and suspending attachment. Fig. 5 is a plan of the same, and Fig. 6 is a diagram of the connections.

The top plate, A, and bottom plates, B E, are connected by the bolts C D. The plates B E are insulated from each other. The bolt C is insulated from A and E. The bolt D is insulated from B. The lower-carbon holder F 40 is sustained by the frame or rods G, depending from B, and the upper-carbon holder H passes through and is in electric contact with A and E. The helices K L are in a shunt-circuit, passing by the spring *a*, thermal switch 45 *b*, from the plate E, and the circuit is by the bolt C to the negative connection at *d*. The current entering by *e* passes by A D E—one or all—to the upper-carbon holder H, through the carbons, and by F G B to C and *d*. The 50 shunt through K L is by *e D E a b K L C to d*.

The carbon-holder H has upon it a rack, into which the pinion M gears, and there is a train

of gearing, 1 2 3 4, between the shaft *f* and the shaft *g* of the brake-wheel *i*, so that this wheel *i* is revolved rapidly for a very slow move- 55 ment of the carbon-holder.

If desired, an escapement-wheel, *t*, may be applied to one of the shafts of the train of gearing, and a vibrator, *t*, to prevent the parts moving too suddenly if the friction-brake is 60 raised; but a fan or fly may take the place of the escapement and vibrator. The shafts of the gearing are journaled in the plates or frames N, that rest upon the middle of the spring O, the supports 8 for which spring 65 are near the ends. This spring is either in two parts or made with a central opening, so as to pass at each side of the holder H and the cores *l l* of the magnets K L. The armature P Q forms the upper part of the frame N or 70 is connected therewith, and it has short cores *p q* passing into the helices K L.

The brake-lever R is pivoted at *s* and pro- 75 vided with an end of iron or other magnetic material, so as to be acted upon by the mag- netism of the armature P Q and lifted to re- lieve the pressure upon the brake-wheel *i* when the armature P Q is sufficiently ener- gized. The spring *t* applies pressure to the 80 brake-lever R, and the turn-button shaft *r* and cord are used to adjust the spring and regu- 85 late the lamp. This pressure upon the brake- wheel is the only adjustment that is required. It may be obtained in any desired manner— such as by a movable weight applied to the 85 brake-lever, or by any other character of spring, or an adjusting-screw and spring. The amount of play allowed to the brake-lever may be determined by the brass pin 10, or a screw may take its place. 90

The armature P Q might be one piece of iron; but I prefer to use two pieces, the ends of which are connected to the non-magnetic frame N at 20, so that the end portions of the armature may become poles that are magnet- 95 ized by induction, and act upon the iron end of the brake-lever R, the frame N being re- moved, as shown, to give the necessary space for this iron end for the brake-lever.

It will now be understood that the plate E 100 forms the back bar between the cores *l l*, and that these cores *l* will attract the armature P Q, and the two parts of said armature will be- come magnetized with opposite poles at the

ends thereof, adjacent to the frame, and the strength of the magnetism will be proportioned to the current passing through the helices in the shunt-circuit.

5 The parts are to be proportioned so that the spring O will support the carbon-holder, gearing, frame, and armature, but it will yield to the attraction of the electro-magnet.

When the carbon is to be put into the holder 10 H, the latter is to be run up, the ratchet-wheel k and pawl n allowing the holder to be moved up; but when the carbon is in place and it is drawn down by the fingers, the friction-wheel will turn under its lever, and the carbon points 15 thus be brought together; but as soon as the fingers are removed the spring O lifts the parts and slightly separates the carbons. When the current is turned into the line, the magnets K L are sufficiently energized to draw the armature 20 down and cause the carbons to touch, and the contact of the carbons being thus made the upper carbon rises in consequence of the magnet K L weakening as the main current through the carbons is established and in proportion to the shunt-current, so the carbon 25 will be drawn down by the magnet or be lifted by the spring O. In connection with this movement the brake-wheel is liberated and allowed to turn and the carbon to descend whenever the armature becomes sufficiently 30 energized to relieve the brake-wheel from the pressure of the spring t and allow it to turn by the weight of the parts acting on the gearing; hence by adjusting this spring the length 35 of arc may be varied, because when the spring pressure on the brake-wheel is strong the arc will be long and a stronger current be required in the shunt to raise the brake-lever than will be needed if the spring-pressure is weak.

40 The thermic switch b is made of a wire of lead or other suitable material that is of a size to offer resistance and that will either soften or melt with the heat developed by the current if the same becomes too great through 45 the shunt, and when the said wire b thus yields the spring a will come into contact with the stud v upon the plate B, and the current will be switched past the lamp and by D E a v B C to d. The ends of the spring a and the plate 50 e² should be notched, and the thermic switch-wire b have heads at both ends, so that the lamp can be restored by simply placing another wire between a and e².

In order to connect the lamp to the ceiling 55 or other support and to allow for its removal, I provide the polygonal heads to the bolts C D, such heads forming the binding-posts if separate wires are used. The corners of one of these heads are in a different position from 60 those upon the other head, so that the lamp cannot be put up the wrong way, and there are openings in the ceiling-plates e³ d² corresponding to the polygonal heads e and d, and there are ledges or ribs at 65 over which the polygonal heads are passed as the bolts are moved along to place in the slotted portions of the ceiling-plate; hence the parts cannot

become disconnected accidentally. These ceiling-plates are screwed to a block of wood or other non-conductor, and the wires or other 70 conductors are fastened to these ceiling-plates.

Only one helix may be used in place of the two helices shown. This may be placed at one side of the carbon-holder, or it may be placed around the same, the carbon-holder 75 passing through a tubular case, the operations of the parts being the same as before described.

While the lamp is being adjusted, or when the lamp is to be extinguished, the switch s² may be turned into contact with the pin s³. 80 This closes the circuit between the plates E and B in consequence of the pivot-stud of the switch being connected to B and insulated where it passes through the plate E, and the stud s³ being upon said plate E. 85

I claim as my invention—

1. The combination, with the carbons and holders in an arc lamp, of a helix in a shunt between the + and — binding-posts, a rack upon the carbon-holder, a train of gearing, 90 and a brake-wheel, the frame for the gearing and spring for supporting the weight of the parts, and an armature-lever acting upon the brake-wheel, substantially as set forth.

2. The combination, with the carbon-holder and a rack upon the same, of a train of gearing, a frame for the same, a spring for sustaining the weight of the moving parts, a divided armature and a helix in a shunt-circuit, and an armature brake-lever in proximity to 100 the magnetic poles of the armature, substantially as specified.

3. The electro-magnets K L and the back bar, E, in combination with the carbon-holder passing through the back bar, the train 105 of gearing and a frame, a spring below the frame, an armature connected to the frame, and a brake wheel and lever, substantially as specified.

4. The combination, in an electric lamp, of 110 an armature made in two parts and united by non-magnetic material, and an armature-lever placed in the magnetic field of the armature and acting to control the movements of the carbon, substantially as specified. 115

5. The combination, in an electric lamp, of a carbon-holder, a train of gearing, and a brake-wheel, a lever and adjustable presser applied to the brake-wheel, and a magnet energized by a current in a shunt-circuit and acting to 120 liberate the brake-wheel, and a spring to raise the carbon, substantially as specified.

6. The combination, with the electric lamp, of the bolts C D, having polygonal heads, in combination with the ceiling-plates e³ d², having corresponding openings slotted and with ledges or ribs, substantially as set forth. 125

Signed by me this 17th day of January, A. D. 1884.

CLINTON M. BALL.
